UNITED STATES PATENT OFFICE.

FRANK WOOD, OF VALLEY FALLS, RHODE ISLAND, ASSIGNOR TO FRANK WOOD MANUFACTURING COMPANY, A CORPORATION OF RHODE ISLAND.

DESIGN FOR TRIMMING.

40,949.

Specification for Design.

Patented Oct. 18, 1910.

Application filed August 13, 1910. Serial No. 577,104. Term of patent 7 years.

To all whom it may concern:

Be it known that I, FRANK Wood, a citizen of the United States, residing at Valley Falls, in the county of Providence and State of Rhode Island, have invented a certain new, original, and ornamental Design for Trimming, of which the following is a specification.

In the accompanying drawing which forms a part of this specification the figure

is a front view of a portion of trimming embodying my new design.

I claim—

The ornamental design for a trimming, as shown.

FRANK WOOD.
